COIN BANK SLOT GUARD

Arthur C. Prince, Chicago, Ill., assignor to Chicago Thrift Company, Chicago, Ill., a corporation of Illinois

Application March 14, 1942, Serial No. 434,672

4 Claims. (Cl. 232—4)

This invention relates to a bank, and primarily to a bank of the pocket type, although it may be embodied in a larger bank.

It has for one object to provide a simple slot guard or safety means.

Another object is to provide a slot guard so arranged that it not merely prevents the withdrawal of coins through the slot, but tends to force or drive the coins forcibly into the bank once they have entered the slot.

Another object is to provide an end plate for a bank upon which the slot guard member is mounted, so that the two may be considered as a unit and installed together in a single operation after having been assembled one upon another.

A still further object is to provide a slot guard member and construction so arranged that the slot guard, although carried on the top or end of the bank, presses against a side wall.

Other objects will appear from time to time throughout the specification and claims.

The invention is illustrated more or less diagrammatically in the accompanying drawing, wherein:

Figure 1 is a side elevation of one form of the bank.

Figure 2 is an enlarged vertical sectional detail taken at line 2—2 of Figure 1.

Figure 3 is a plan view of the plate which carries the slot guard.

Figure 4 is a vertical section taken at line 4—4 of Figure 3.

Like parts are indicated by like characters throughout the specification and the drawing.

While the invention may be embodied in many bank constructions, in the particular form here shown the bank comprises three sections, 1, 2, and 3, which may be relatively movable with respect to each other. The invention is not in any sense limited in its application to a multi-part or telescopic bank. The section 3 is provided with a slot 4 which as shown in Figures 1 and 2 is inclined downwardly away from the top or end of the bank. The upper or outer end of the section 3 is closed by a plate 5, which is preferably a disc-like member, and beneath which or in contact with which is mounted a disc-like member 6 upon which the slot guard construction is mounted, as will be described below.

The plates 5 and 6 are held in place against a shoulder formed by bending the upper portion of the section 3 outwardly, and they are held in place against the shoulder by a flange 7, which

is formed by bending downwardly, laterally, and inwardly the outer end of the member 3.

The plate 6 is formed to provide a pair of channel-like depressions 8, 8 which may terminate at perforations 9, 9, and which at their other ends run into or connect with a notched or cut-away portion 10.

The slot guard includes a spring which is provided with ends 11, 11, each of which projects through one of the perforations 9 and lies in one of the depressions 8. Where they approach each other, the spring sections 11 are curved to provide loops 12 and are then bent downwardly to provide a loop 13, which extends as shown in Figures 2 and 4 below the rest of the spring and overlies the slot 4. The plate 6 may be provided with a raised portion 14, which as shown in Figures 2, 3, and 4, overlies the loops 12 of the spring and assists in holding the spring in place. This member 14 for some purposes may be omitted.

It will be realized that whereas I have described and shown a practical and operative embodiment of my invention and the method for carrying it out, nevertheless many changes may be made in the size, shape, number and disposition of parts and in the details and steps of such method without departing from the spirit of my invention. I therefore wish my description and drawing to be taken as in a broad sense illustrative or diagrammatic, rather than as limiting me to my precise showing.

The use and operation of the invention are as follows:

In general the slot guard mechanism may be applied to a bank of any shape, and it is not necessary that the bank be cylindrical. Also it need not be applied to a telescopic bank, and the one shown is merely an example of a possible bank.

When the slot guard arrangement is applied a portion of it rests yieldingly over or extends across a slot through which coins or tokens are to be inserted. When a coin is inserted it is pushed into the slot 4 and against the loop 13 of the spring and displaces the spring, moving it inwardly and upwardly, clockwise from the position of Figure 2, until the spring has been sufficiently displaced to permit a coin to enter. At the instant that the coin has been inserted sufficiently to clear the inner edges of the slot, the loop 13 is no longer held upward, and is free to spring back toward its original position, and in doing so it forcibly drives the coin inwardly and downwardly into the bank. This is an important feature, because it prevents tam-

pering with the slot guard by the insertion or partial insertion of a coin or other member.

The slot guard prevents removal of coins or tokens from the bank, because it lies across the slot whenever it is not actually being held away by a coin. Once it has resumed the position of Figure 2, no manipulation of coins within the bank can move it to permit their withdrawal, and the clear portion of the slot is not sufficiently large to permit the extraction of a coin; since the spring lies close to the bank portion 3, even by accident the coin may not slip under the edge of the member 13.

In the assembly of the device the parts are made substantially as shown, with the flange 7 not yet in the downward or closed position. The disc 6 is given a suitable shape generally corresponding to the cross section of the bank, and the spring which includes the arms 11 and the loops 12 and 13, is arranged in the position shown. The ends 11 passing through the perforations 9 tend to locate the spring and the raised shoulder-like portion 14 engaging parts of the loops 12 tends to prevent outward movement of the spring, which would complete displacement. The member 14 may be omitted, and for many purposes it would be omitted and is unnecessary, because obviously once the disc 6 has been placed in position, the spring is held against outward displacement, by the bank section 3 itself. However, for convenience of installation and assembly, an enlargement or shoulder such as that 14 may be used if desired.

When the spring has been assembled on the disc 6, the latter is moved into place against the shoulder adjacent the upper end of the member 3. If desired, a plate 5 may be added. Such plate primarily covers the exposed parts of the spring and gives the bank a more finished appearance. It may also be a name plate and may carry advertising or other markings, if desired. When the plate 5 is in place, if one is to be used, the flange 7 is rolled or turned downward to the position shown in Figures 1 and 2, and the closure for the upper end of the bank is thus completed, and the slot guard is held against tampering and removal.

I claim:

1. In combination in a coin bank, means defining a wall, a slot cut in said wall, a slot guard assembly for said slot, said assembly including a plate, said plate having a cut-away portion at one edge, and a pair of perforations spaced away from its edge, said plate being shaped to provide grooves extending one from each of said perforations to said cut-away portion, and a spring extending through said perforations and lying, in part, in said grooves, a portion of said spring extending from said plate and overlying said slot, said spring portion biased to lie over said slot and sufficiently flexible to be moved away from said slot by an entering coin.

2. In combination in a coin bank, means defining a wall, a slot cut in said wall, a slot guard assembly for said slot, said assembly including a plate, said plate having a cut-away portion at one edge, and a pair of perforations spaced away from said edge, said plate being shaped to provide grooves extending one from each perforation to said cut-away portion, and a spring, said spring having two branches, one in each of said grooves, and extending through one of said perforations, a portion of said spring extending from said plate and overlying said slot, said spring portion biased to lie over said slot and sufficiently flexible to be moved away from said slot by an entering coin.

3. In combination in a coin bank, means defining a wall, a slot cut in said wall, a slot guard assembly for said slot, said assembly including a plate, said plate having a cut-away portion at one edge, and a pair of perforations spaced away from said edge, said plate being shaped to provide grooves extending one from each perforation to said cut-away portion, and a spring, said spring having two branches, one in each of said grooves, and extending through one of said perforations, a portion of said spring extending from said plate and overlying said slot, said spring portion biased to lie over said slot and sufficiently flexible to be moved away from said slot by an entering coin.

4. In combination in a coin bank, means defining a wall, a slot cut in said wall, a slot guard assembly for said slot, said assembly including a plate, said plate having a cut-away portion at one edge, and a pair of perforations spaced away from said edge, said plate being shaped to provide grooves extending one from each perforation to said cut-away portion, and a spring, said spring having two branches, one in each of said grooves, and two ends, extending one through each of said perforations, and a pair of loop portions intermediate said ends, said loops bearing against the inner surface of said plate, there being a shoulder formed in said plate, said loops engaging said shoulder and being held against outward displacement thereby, a portion of said spring extending from said plate and overlying said slot, said spring portion biased to lie over said slot and sufficiently flexible to be moved away from said slot by an entering coin.

5. A slot guard assembly adapted for insertion in a coin bank comprising a supporting member, a notch in the periphery of said member, and a pair of perforations positioned in said member away from its periphery, said member formed to provide a pair of grooves, each extending from one of said perforations to said notch, and a slot guard spring positioned partly in said notch and partly in said grooves, extending through said perforations, and provided with an integral yielding portion extending away from the surface of said member.

ARTHUR C. PRINCE.
